P. ARBON

DRILLING JAR

Filed May 5, 1925

Paul Arbon Inventor

By Ralph J. Bassett Attorney

UNITED STATES PATENT OFFICE.

PAUL ARBON, OF TULSA, OKLAHOMA, FIDELITY NATIONAL BANK AND TRUST COMPANY, OF KANSAS CITY, MISSOURI, AND LORNE M. MCLEOD, OF TULSA, OKLAHOMA, EXECUTORS OF SAID PAUL ARBON, DECEASED, ASSIGNEES TO PAUL ARBON & COMPANY, OF TULSA, OKLAHOMA, A CORPORATION OF OKLAHOMA.

DRILLING JAR.

Application filed May 5, 1925. Serial No. 28,123.

This invention relates to the construction of that type of drilling jar known as the T-head weldless jar.

The object of the present invention is to provide certain details of construction found essential to the successful operation of jars of the type above mentioned, and resides principally in the provision for the rapid drainage or elimination of the mud and water which normally destroys the function of the apparatus.

In the actual use of drilling jars, it has been found that unless the mud and water is provided with a means of quick egress then the necessary impulse which a jar is presumed to provide will not be present. This is particularly true in the drilling jar of the present day, which is made of a special alloy steel and subsequently heat treated. These jars are provided with little lateral play and the joints are very exactly aligned to eliminate wear and buckling of the parts under the tremendous weight under which they operate. The destruction of a drilling jar due to faulty construction is a very expensive proposition inasmuch as the conventional well of today is on an average more than 2500 feet deep. Obviously, the collapse of a jar at such a depth will result in a lengthy fishing job or perhaps in the total destruction of the well.

The present invention provides for the escape of the mud and water at all points and in practically every direction and resides generally in the provision of elongated flutes in the male member and corresponding perforations in the female member.

Reference will be had to the accompanying drawings forming a part of this specification and wherein like numerals of reference designate corresponding parts throughout the several views, in which,

Figs. 1 and 2 are side elevations, parts being broken away in section, and

Fig. 3 is a transverse sectional view on line 45 3—3 of Fig. 1.

Fig. 4 is a section showing a modified arrangement of flutes.

The upper or female section of the present jar includes the tapered screw threaded pin 1 at the upper extremity, the angular wrench engaging portion 2, spaced by the cylindrical collar 3 and the tubular lower extremity

formed with elongated side openings 4 and 5 and lower opening 6 through which the neck of the male member passes. The tubular portion of the female member is provided with spaced rows of perforations at those portions of the wall between the side openings 4 and 5 and these rows of perforations extend the full length of the cylinder wall. 55 60

The male member is formed at its lower extremity with the threaded box or socket 7, adjacent wrench engaging angular portion 8 and annular stop collar portion 9. The portion of the male member above the collar 9 is gradually reduced as at 10 to a diameter equivalent to the diameter of the opening in the female member and then continues into an elongated cylindrical shank portion 11. The upper extremity of the male member is 70 formed with integral lateral wings 12 and 14 which engage and travel in the slots 4 and 5 of the female member.

Flutes 15 extend the full length of the male shank member to the point of the greatest diameter in the collar 9 and are spaced and arranged to register with the longitudinal rows of perforations in the female member. Additional flutes 16 are also provided in the collar 9 of greater depth than the shank flutes 80 and these flutes 16, it will be noted, are spaced intermediate the flutes 15.

Obviously during the operation of the present jar, the mud and water is provided with means of escape at practically every point 85 and any grit which normally might be inclined to pack between the walls will gradually be removed by the flow of water and mud through the flutes and out of the perforations, such flow naturally tending to spread to adjacent surfaces and thus maintain same in a substantially clean condition. More important perhaps is the ability by means of the above mentioned construction of securing the desired jarring impact for which the implement is designed.

Numerous changes in the arrangements of ports and flutes might be contemplated under the present invention, the present illustration being designed to illustrate the function and operation of the invention in a general way.

What I claim as new and useful and desire to secure by Letters Patent is:—

1. A drilling jar including a tubular female

member formed with a plurality of spaced perforations in its side walls, and a male member arranged to operate within said female member and formed with grooves which register with said perforations, said grooves and certain of said perforations constantly communicating.

2. In a drilling jar including a female member formed with a plurality of rows of perforations in its side walls, a male member arranged to travel in said female member formed with flutes which register at all times with certain of said perforations.

3. In a drilling jar, a female member including a cylindrical portion having oppositely arranged openings and being formed with rows of spaced perforations extending longitudinally of said cylindrical portion at points intermediate said openings, and a male member formed with lateral extensions adapted to travel in the openings in said female member and being provided with flutes spaced to register with the perforations in the female member.

4. In a drilling jar, a female member including a cylindrical portion having elongated openings in its wall formed with rows of perforations extending throughout its entire length spaced intermediate said openings, a male member formed with a stop collar at an intermediate point and wings at its upper end adapted for travel in the openings in said female member, the shank of said male member being fluted from a point at approximately the greatest diameter of said collar to its upper extremity and the flutes being adapted to register with the rows of perforation in said female member, and additional flutes spaced intermediate the beforementioned flutes and extending the length of said collar portion.

5. In a drilling jar, a female member in-

cluding a tubular portion having one end opened and the other end closed, the tubular portion adjacent the open end forming a tubular bearing, a male member including a shank arranged to reciprocate in the tubular portion of the female member, and means for preventing the shank from turning in the tubular portion, said tubular bearing having perforations in its side walls, and said shank having longitudinal grooves communicating with said perforations at all times.

6. A drilling jar as claimed in claim 5, in which the grooves extend throughout substantially the entire length of the shank, the walls of the tubular portion of the female member between the tubular bearing and closed end being perforated, and these perforations registering with said grooves.

7. In a drilling jar, a female member including a tubular portion having elongated openings in its wall and formed with rows of perforations extending throughout substantially its entire length and spaced intermediate said openings, a male member formed with a stop collar and provided with wings at one end for travel in the openings in said female member, the shank of said male member being grooved from the stop collar to its extremity and the grooves registering with said rows of perforations.

8. A drilling jar including a tubular female member formed with a plurality of spaced longitudinally disposed rows of perforations in its side walls, and a male member arranged to operate within said female member and formed with longitudinal grooves which register with said rows of perforations, said grooves and certain of said perforations constantly communicating.

In testimony whereof I affix my signature.

PAUL ARBON.
